UNITED STATES PATENT OFFICE.

RUDOLPH ULLRICH, OF NEWARK, NEW JERSEY.

STYLOGRAPHIC FOUNTAIN PEN.

1,425,150.

Specification of Letters Patent. Patented Aug. 8, 1922.

Application filed July 1, 1921. Serial No. 481,745.

To all whom it may concern:

Be it known that I, RUDOLPH ULLRICH, a citizen of the United States, and a resident of Newark, in the county of Essex and State of New Jersey, have made and invented certain new and useful Improvements in Stylographic Fountain Pens, of which the following is a specification.

My invention relates to stylographic fountain pens and has for its object to provide a pen of this character which is efficient in operation, simple in construction, and, embodying a minimum number of parts, may be economically manufactured.

A further object is to provide a stylographic pen so constructed that the tip or stylus holder will always protrude from the pen proper a pre-determined amount, thus allowing the pen to be easily taken apart and assuring that it will be properly reassembled.

A further object is to provide a stylographic pen having a head section with an abutting ledge and against which the stylus tip is adapted to contact, thus providing a chamber of fixed dimensions and adapted to receive the weighted needle therein and provide for the proper amount of end play for the same.

A further object is to improve generally and enhance the utility of articles of the class to which the present invention relates, and with the foregoing and other objects in view, my invention consists in the improved stylographic fountain pen illustrated in the accompanying drawing and hereinafter described and claimed, and in such variations and modifications thereof as will be obvious to those skilled in the art to which my invention relates, it being understood that changes may be made within the scope of what is claimed without departing from the spirit of the invention.

In the drawing accompanying and forming a part of this application:

Figure 1 is a view in vertical longitudinal section of a stylographic fountain pen embodying the characteristic features of my invention;

Figure 2 is an enlarged view in longitudinal section of the lower portion of the same but taken on a plane at 90° to the plane of the section of Figure 1;

Figure 3 is a detail view in elevation of the stylus holder or tip

Figure 4 is a top plan view thereof.

Referring specifically to the several views, wherein similar reference numerals designate corresponding parts throughout, my improved pen is composed of a barrel 6 having the usual screw threads 7 at the lower and open extremity thereof. A cap 8 is internally threaded and adapted to close and protect the lower extremity of the pen or to wedgedly engage the upper and remote extremity of the pen when in use.

The head section 9 is formed with the reduced ledge 10 fitting within and wedgedly engaging the open extremity of the barrel 6. The protruding extremity of the head section is externally tapered as at 11, so as to present a symmetrical appearance with regard to the remaining portions of the pen. The lower extremity of the head 10 is bell mouthed as at 12, thus preventing any danger of ink reaching the finger-engageable portion of the pen, and presenting an increased bearing surface for contact with the cap 8 when the pen is not in use. The head 10 is provided with a bore extending therethrough, the innermost portion 13 of which is restricted in diameter and communicates with the barrel of the pen 6 or the ink reservoir. Adjacent the restricted portion 13 is an intermediate bore 14, the two having the shoulder or ledge 15 therebetween, which, in conjunction with the intermediate portion 14, and adjacent parts, defines an annular air chamber, as will be hereinafter more fully explained. The bore immediately adjacent the annular air chamber 14 is somewhat enlarged and threaded as at 16, while the lower and outer extremity of the bore is further enlarged so as to form an air entrance conduit 17.

The stylus holder or tip 18 is externally threaded as at 19 and adapted to fit within and engage the threaded portion 16 of the bore of the head section. The protruding extremity of the tip is tapered as at 20 so as to present a neat and symmetrical appearance in conjunction with the remaining portions of the pen, and supports at its outermost extremity the capillary writing tube 21. The remote or inner extremity of the tip is provided with a cylindrical projection of reduced diameter 22 which is adapted to abut against the ledge or shoulder 15 of the head section bore and, in conjunction with the intermediate portion 14 of the bore 10, and adjoining portions of the threads 19, form the annular air chamber as previously

described. The body of the holder 18 is of less diameter than the outer portion 17 of the bore, so that air may enter between the tip or holder and the adjacent side walls of the bore, thus forming the air inlet conduit as previously described. A suitable duct 23 extends axially along the threaded portion 19 of the tip and provides for the entrance of air into the annular air chamber 14.

The reduced upper extremity or cylindrical projection 22 of the tip is provided with the opening or notch 24 extending through the side walls thereof, and which notch is turned or out of alinement with the notch 23. Communicating with the writing tube 21 is the duct 25, the upper extremity of which is enlarged to form the weight-receiving chamber 26 and with which the notch 24 above mentioned communicates, thus providing for the entrance of air from the annular air chamber 14 directly into the weight-receiving chamber 26. The rear extremity of the reduced cylindrical projection 22 abuts against the ledge or shoulder 15 of the head section and accordingly holds the tip protruding from the head section a predetermined amount and also insures that the size of the combined weight-receiving chambers 13 and 26 will always remain constant even though the pen be taken apart and re-assembled, thus insuring the proper amount of end play or pumping action of the weight and stylus needle.

The head section 9 is preferably formed from a solid blank and the rear extremity thereof is milled and then routed out as at 27, so as to form an integral bridge or retaining end stop 28, this end stop not in any way interfering with the entrance of ink into the weight-receiving chambers 13-26, but at the same time limiting the endwise play or pumping action of the weight 29. The stylus needle 30 is secured to the weight 29 and is adapted to provide a steady and constant flow of ink to the writing tube 21 in the usual and well-known manner.

The head section as thus formed may be directly inserted within the ink reservoir of the fountain pen, or, as illustrated in Figures 1 and 2 of the drawings, the head section may be provided with a somewhat reduced end 31 and to which is secured the customary rubber sack 32, thus forming what is known as a self-filling stylographic fountain pen. When used as a self-filling stylographic fountain pen, the air inlet conduit 17, duct 23, annular air chamber 14, and duct 24, are adapted to act as an inlet for the ink, although it will be readily appreciated that the ink cannot under any circumstances flow outwardly through these ducts and passages, due to the particular arrangement of the same.

By forming the head section and stylus tip as thus described, I am able to materially reduce the number of parts involved in the construction of the ordinary stylographic fountain pen, and, further, have provided a weight-receiving chamber of predetermined size so as to prevent any danger or likelihood of the needle 30 moving upwardly beyond the lower wall of the writing tube 21 and also preventing it from protruding an undue distance therebeyond, thus providing for the proper working and writing of the stylus point, and, further, insuring a steady and uniform flow of ink. Furthermore, the tip will always protrude from the head section a predetermined amount so that the symmetrical appearance of the pen and the proper relation between the tapered portion 11 of the head section and the extreme tip of the stylus will be maintained, all of which, and particularly in connection with the fact that the pen may be most economically manufactured, provides an improved and efficient writing instrument.

Having thus described and explained my invention, I claim and desire to secure by Letters Patent:

1. A stylographic fountain pen comprising a barrel, a head section fitting therein and provided with a bore extending therethrough and having an end stop extending across the open inner extremity of the bore, the bore of said head section provided with a shoulder intermediate its ends, a stylus tip threadedly engaging the lower portion of the bore of the head and provided with a reduced cylindrical projection abutting against the said shoulder of the bore of the head section and held protruding from the said head section the proper amount by said shoulder, said stylus tip provided with a bore therein and forming with the bore of the head section a weight-receiving chamber of predetermined size and providing for the proper end play of the weighted needle, and a weighted needle carried in said weight-receiving chamber, with the needle portion protruding through the lower extremity of said stylus tip, and means for allowing ink and air to pass inwardly between the stylus tip and adjacent walls of the bore of the head and preventing ink from returning by the same passage, substantially as described.

2. A stylographic fountain pen comprising a barrel, a head section fitting therein and having a bore extending therethrough, the remote or upper section of said bore of restricted size, and the intermediate portion enlarged to form an annular air chamber with a shoulder at one extremity thereof, the lower portion of the bore of the head counter-bored and internally threaded, the lowermost extremity of the bore further enlarged and forming an air and ink inlet conduit, a stylus tip provided with an external thread

thereon engaging the threaded portion of said bore and forming a cylindrical projection at the rear extremity thereof fitting within the intermediate and enlarged portion of said bore and abutting against the said shoulder, said reduced cylindrical projection and adjacent walls of the bore forming an annular air chamber, said tip provided with an open-ended chamber communicating with the upper and reduced extremity of the bore of the head section and forming in connection therewith a weight-receiving chamber, an end stop extending across but not closing the inner extremity of the bore of the head section, said weight-receiving chamber of fixed and non-adjustable size, and a weight located within said weight-receiving chamber and limited in end play by the fixed and predetermined size of said weight-receiving chamber, and a 20 stylus needle carried by said weight and projecting through the stylus tip, an air inlet duct communicating with said annular air chamber, and a second duct out of alignment with the aforementioned duct and communicating with the chamber of the stylus tip. 25

Signed at New York, borough of Manhattan, in the county of New York and State of New York, this 30th day of June, A. D. 1921.

RUDOLPH ULLRICH.
